OCULAR TOY

Herbert A. Papke, Grand Rapids, Mich.

Application February 23, 1946, Serial No. 649,493

4 Claims. (Cl. 46—1)

1

The present invention relates to toys and more particularly to a toy presenting an optical illusion when in use.

The primary objects of the instant invention are to provide such a toy which is novel in character; to provide such a toy which is entertaining in use; to provide such a toy which is simple in construction; and, to provide such a toy which is economical in manufacture.

An illustrative embodiment of the invention is shown in the accompanying drawing, wherein:

Figure 1 is a perspective view of the toy;

Figure 2 is a longitudinal sectional view thereof, partly broken away;

Figure 3 is a perspective view of the type of lens used in the toy shown in Figure 2;

Figure 4 is a perspective view of an alternate or substitute type of lens; and

Figure 5 is likewise a perspective view of another alternate or substitute type of lens.

Referring then to the drawing wherein like parts of the toy shown are designated by the same numerals in the several views, the same comprises a tubular cylindrical body 10 of any suitable material such as plastic, metal or cardboard having an inner surface 11 adapted to reflect light.

One end of the body 10 is provided with an annular internal swaged groove 12 within which is seated a concave or dished disc 13 of flexible material provided with a centrally disposed circular aperture 14 which disc is here shown as faced by a transparent flexible disc 15 of isinglass or the like likewise seated within the groove 12 and the body 10 is further provided with an internal swaged groove 16 adjacent its other end within which is seated a translucent disc lens 17 having parallel corrugations 18 on one face thereof.

The body 10 is further provided with an outer pair of spaced internal annular swaged grooves 19, 20 and a collar 21 having an internal diameter slightly greater than the external diameter of the body 10 is provided with a plurality of spaced internal annular swaged grooves 22, 23, 24 and 25 whereby the collar may be secured to one end of the body 10 by rotatably fitting the same thereon with the grooves 19, 20 of the body in registration and embracing engagement with the grooves 22, 23 of the collar, all as best shown in Figure 2.

2

Flexible transparent discs 26, 27 likewise of isinglass or the like are seated in each groove 24, 25 and a plurality of colored glass pieces 28 such as marbles, glass chips or the like are loosely disposed between the discs 26, 27 whereby they may be tumbled upon rotation of the collar 21 relative to the body 10.

Substitute or alternate type lenses 29, 30 having cross-corrugated and concentric corrugated 10 faces are shown in Figures 4 and 5.

In use, the user looks through the aperture 14 toward a source of light and upon rotating the collar 21 relative to the body 10, varying and pleasing color effects are presented making a toy 15 that is novel in character and entertaining in use.

It will thus be seen that the toy herein shown and described is simple in construction and economical in manufacture, and while but one specific embodiment of the invention has been herein 20 shown and described, it will be understood that certain details of the construction shown may be altered or omitted without departing from the spirit of the invention as the same is defined by the following claims.

25 I claim:

1. A toy comprising a tubular cylindrical body having a light reflecting inner surface, a transverse apertured disc disposed adjacent one end thereof, a pair of spaced transverse transparent 30 discs disposed adjacent the other end thereof, a transverse translucent disc disposed intermediate the length of the body, and a plurality of vari-colored glass pieces disposed between the pair of spaced discs.

35 2. A toy comprising a tubular cylindrical body having a light reflecting inner surface, a transverse apertured disc disposed adjacent one end thereof, a pair of spaced transverse transparent discs disposed adjacent the other end thereof, a transverse translucent corrugated disc disposed 40 intermediate the length of the body, and a plurality of vari-colored glass pieces disposed between the pair of spaced discs.

3. A toy comprising a tubular cylindrical body 45 having a light reflecting inner surface, a transverse apertured disc disposed adjacent one end thereof, a transverse transparent disc disposed forwardly of the apertured disc, a pair of spaced transverse transparent discs disposed adjacent 50 the other end thereof, a transverse translucent

corrugated disc disposed intermediate the length of the body, and a plurality of vari-colored glass pieces disposed between the pair of spaced discs.

4. A toy comprising a tubular cylindrical body having a light reflecting inner surface, a transverse apertured disc disposed adjacent one end thereof, a pair of spaced transverse transparent discs disposed adjacent the other end thereof, a transverse translucent corrugated disc disposed intermediate the length of the body, and a plurality of vari-colored glass marbles disposed between the pair of spaced discs. 10
